UNITED STATES PATENT OFFICE.

KARL A. NORRMAN, OF LYNN, MASSACHUSETTS, ASSIGNEE TO GENERAL ELECTRIC COMPANY, A CORPORATION OF NEW YORK.

PULVERIZED-FUEL-COMBUSTION CHAMBER FOR GAS-TURBINES.

1,180,792.

Specification of Letters Patent. Patented Apr. 25, 1916.

Application filed September 19, 1913. Serial No. 790,808.

To all whom it may concern:

Be it known that I, KARL A. NORRMAN, a subject of the King of Sweden, residing at Lynn, county of Essex, State of Massachusetts, have invented certain new and useful Improvements in Pulverized-Fuel-Combustion Chambers for Gas-Turbines, of which the following is a specification.

This invention relates to apparatus for generating an expansive gas for the purpose of actuating a turbine or other engine. Many suggestions have been made heretofore for using pulverized fuel for this purpose, especially finely powdered coal, and my invention aims to utilize such coal dust, feeding it in an improved manner to a combustion chamber of improved construction from which the products of combustion are led to the engine.

The essential points of the invention are the receptacle for the powdered coal in which it is held under pneumatic pressure and from which it is fed by a rotary charging device into a pipe through which compressed air is flowing. The current of air sweeps the coal dust into a circular combustion chamber, entering said chamber on a tangent, so that a whirling motion is imparted to the dust-laden air which facilitates complete combustion. If there are any unconsumed particles they are carried by centrifugal force to the outer wall of the chamber and drop down with the ashes into funnel-shaped recesses or pockets in the bottom of the chamber adjacent to said outer wall and communicating with ash receivers. Suitable valves enable the receivers to be cut off from the combustion chamber when the ashes and refuse are to be emptied. A discharge pipe for the expansive hot gases of combustion extends down centrally into the combustion chamber so that the gases can escape with no danger of carrying ashes or unburned coal with them.

In the accompanying drawing Figure 1 is a diagrammatic view, partly in vertical section, of an apparatus embodying my invention, and Fig. 2 is a horizontal cross section of a portion of the same.

The coal dust 1 is stored in a receptacle 2, which has a filling opening at the top closed by a lid 3. A clamping screw holds the lid in place so that fluid pressure led through a branch pipe 4 from a main pipe 5 may fill the receptacle above the fuel. By thus

subjecting the fuel to pneumatic pressure, it can be easily and successfully fed down into the air pipe to be blown into the combustion chamber. This feature of the invention requires a large plant to have a good sized receptacle capable of holding a supply of fuel sufficient to last some twelve hours even when the turbine is running under full load. A receptacle of this capacity will not be more voluminous than the combustion chamber itself, and can be opened and refilled once or twice in twenty-four hours during shut down periods of the combustion chamber to which it is connected. With large units more than one combustion chamber is necessary and the load usually fluctuates enough to allow one or more chambers to be shut down now and then for cleaning and refilling. The receptacle has a hopper-shaped bottom 6 which opens into the pipe 5. The delivery end of a suitable air compressor (not shown) is connected to said pipe. In the opening between the hopper and the air pipe is a small toothed roller or valve 7 which can be rotated at a varying speed by any suitable device, such as the pulley 8 and belt 9. The speed of this rotary charging device can be regulated in any suitable manner.

A stop valve 10 is opened to start the flow of air through the pipe 5 when the apparatus is to begin operating. The current of air picks up the coal dust fed in by the rotary valve and blows it into the circular combustion chamber 11, entering it tangentially, as shown in Fig. 2. This chamber is made of iron, lined with a thick layer 12 of refractory material. Its top is conical, and the air pipe enters at the upper end, so that the mixture of air and coal dust spreads rapidly as it whirls around and settles downwardly. The mixture can be ignited at starting by any suitable means, such for example by starting on oil fuel admitted through pipe 25 and ignited by the spark plug 13 connected to a suitable source of electric current. After once being fired, the incoming stream of combustible continues to burn steadily. The products of combustion escape from the chamber through a discharge pipe 14 which depends centrally from the top of the chamber, and is not only covered with refractory material but has a water jacket 15 to keep it cool. The open lower end of the discharge

pipe, through which the gases enter it, stands but little above the bottom of the chamber so that the combustible must be completely mixed and consumed before the products of combustion can escape from the chamber. The upper end of the discharge pipe connects with one or more expansion nozzles 16 which direct the gases upon the buckets 17 of the turbine 18. The centrifugal force due to the whirling motion of the contents of the chamber throws the ashes and unconsumed fuel against the walls of the chamber where they drop into the pockets 19 formed in the bottom of the combustion chamber. At the bottom of each pocket is an opening 20 from which a pipe 21 runs down to a receiver 22 in which the ashes and other refuse collect. The pipes 21 and receivers 22 are preferably water-jacketed, as shown, and each pipe can be closed by one or more water-cooled gate valves 23 when the receiver is to be cleaned out through the man-hole 24.

In accordance with the provisions of the patent statutes I have herein described the principle of operation of my invention, together with the apparatus which I now consider to represent the best embodiment thereof; but I desire to have it understood that the apparatus shown is only illustrative and that the invention can be carried out by other means.

What I claim as new and desire to secure by Letters Patent of the United States, is:—

1. Apparatus for burning powdered fuel, comprising a circular combustion chamber, means for blowing the fuel into said chamber on a tangent, pockets at the bottom of the walls of said chamber for receiving ashes and other refuse and a central discharge pipe leading from a point near the base of the chamber up through the top thereof.
2. An apparatus for burning powdered fuel comprising a circular combustion chamber, a discharge pipe extending from a point adjacent the base of the chamber up through the top thereof, means for blowing in fuel at a tangent near the top of the chamber, and a receiving pocket at the base of the chamber.
3. In an apparatus of the character described, the combination of a circular cas-

ing, a discharge conduit extending from the upper end of the casing to a point adjacent the lower end thereof thereby forming with the casing an annular combustion chamber, means for blowing fuel into said annular combustion chamber adjacent the top thereof and at a tangent thus setting up a whirling movement of the contents of the chamber, and means forming pockets at the bottom of the chamber.

4. Apparatus for burning powdered fuel, comprising a circular combustion chamber having a conical top, means for blowing in the fuel at a tangent near the upper end of said chamber, and a central discharge pipe passing up through said top.

5. Apparatus for burning powdered fuel, comprising a circular combustion chamber having a conical top, means for blowing in the fuel at a tangent near the upper end of said chamber, and a central discharge pipe passing up through said top and extending down nearly to the bottom of said chamber.

6. Apparatus for burning powdered fuel, comprising a circular combustion chamber having a conical top, means for blowing in the fuel at a tangent near the upper end of said chamber, a central discharge pipe passing up through said top and extending down nearly to the bottom of said chamber, and a water jacket for said pipe.

7. In an apparatus of the character described, the combination of a circular combustion chamber, a central discharge pipe extending from a point adjacent the bottom thereof up through the top of the chamber, means for blowing fuel into said chamber on a tangent whereby a whirling movement of the contents of the chamber is produced and the ashes or other refuse is thrown against the walls of the chamber by centrifugal force, pockets at the bottom of the chamber to receive the refuse or ashes, and receivers connected to said pockets.

In witness whereof, I have hereunto set my hand this the sixteenth day of September, 1913.

KARL A. NORRMAN.
